UNITED STATES PATENT OFFICE

1,990,137

WRENCH

Norman John Schrubb, Meadville, Pa.

Application April 14, 1934, Serial No. 720,630

1 Claim. (Cl. 81—160)

This invention appertains to new and useful improvements in wrenches, and more particularly to a wrench of the slidable outer jaw type.

The principal object of the present invention is to provide a slidable outer jaw type of wrench wherein the outer jaw is spring projected and the adjusting nut therefor is released from connection therewith.

Other important objects and advantages of the invention will become apparent to the reader of the following specification.

In the drawings:

Figure 1 represents a side elevational view of the novel wrench.

Figure 2 represents a side elevational view of the wrench, shown partly in section.

Figure 3 represents a cross sectional view taken substantially on line 3—3 of Figure 2.

Figure 4 represents a sectional view taken substantially on line 4—4 of Figure 1.

Figure 5 represents a perspective view of the spring connected lug.

Figure 6 represents a fragmentary top plan view of the wrench.

Referring to the drawings wherein like numerals designate like parts, it can be seen in Figure 2, that numeral 5 represents the usual handle which is provided with an undercut channel 6 therein defining an elongated slot 7 through the top side of the handle.

Numeral 8 represents an inner jaw of the wrench, while numeral 9 represents the outer jaw provided with the shank 10 having the teeth 11 with which the internal threads of the adjusting nut 12 are engageable, this nut circum-scribing the shank in the manner substantially shown in Figure 2, and being operable at the rear of the shank slideway 13 and partly within the transverse channelway 14 in the handle 5. In this channelway 14 are secured two arcuate-shaped spring leaves 15 by a suitable screw 16 and as is clearly shown in Figure 4, the nut 12, at its inner side, has a longitudinally extending cut-away portion 17. However, the spring 15 serves to urge the knurled nut 12 outwardly so that its internal threads will mesh with the teeth 11 of the outer jaw shank 10.

Numeral 18 represents a lug having an opening therein through which the machine screw 19 is disposed and threaded into the rear end of the

shank 10, as in the manner clearly shown in Figure 2. This lug 18 has a base portion 20 from which extends the member 21 having right-angularly disposed pins 22 extending therefrom. The member 21 is provided with a pair of side members 23 which engage within the undercut channel 6 to prevent the lug 18 from becoming displaced from the wrench handle. The pins 22 project through the end convolutions of a spring 24 located within the channel 6, with one end impinging against one end of the channel, while the opposite end impinges against the member 21 on the lug base 20.

Thus it can be seen that when adjustment is required, of the outer jaw, the nut 12 can be forced inwardly of the transverse channel 14, so that the internal threads thereof will disengage from the teeth 11. The spring 24 will now exert its tension on the shank 10 and force the same outwardly so that the outer jaw will automatically space itself from the inner jaw 8. Fingers 20 extend laterally from the handle 5 and are in a position to serve as retainers or guides for the rear end of the nut 12, as in the manner substantially shown in Figure 1.

While the foregoing specification sets forth the invention in specific terms, it is to be understood that numerous changes in the shape, size and materials may be resorted to without departing from the spirit and scope of the invention as claimed hereinafter.

What is claimed is:—

A wrench of the character described comprising a handle, an inner jaw on the handle, an outer jaw, said outer jaw being provided with a toothed shank, a slideway on the handle for the said shank, an internally threaded nut for the shank and displaceable relatively thereto whereby the said shank can be fed forwardly or rearwardly through the said slideway, said handle being provided with a bore therein, a spring in the bore, a lug, said handle being provided with an undercut slot opening into the bore of the handle, a projection on the lug slidable in the said slot, a pin on the projection extending from the lug for disposition through end convolutions of the said spring, means securing the said lug to the shank and side members on the said pin disposed in the slot to prevent displacement of the pin therefrom.

NORMAN JOHN SCHRUBB. 50
